UNITED STATES PATENT OFFICE.

GEORGE DAVIS AND LAURENCE M. SAMUEL, OF NEW YORK, N. Y., ASSIGNEES TO
ENGLERT MANUFACTURING COMPANY, OF PITTSBURGH, PENNSYLVANIA.

GRID PLATE FOR BATTERIES.

Application filed September 16, 1921. Serial No. 501,135.

To all whom it may concern:

Be it known that GEORGE DAVIS and LAURENCE M. SAMUEL, citizens of the United States, residing at New York city, in the county of New York and State of New York, have invented certain new and useful Improvements in Grid Plates for Batteries, of which the following is a specification.

This invention relates to new and useful improvements in grid plates for storage batteries, and the primary object is to provide a grid plate of such construction as will cause the ingredients of the battery box to more closely adhere to said plate, thus affording the most efficient results.

A further object of the invention resides in providing a grid plate provided with diagonally disposed ribs, and a still further object resides in providing such ribs on both faces of the plate, the ribs being triangular in cross section with their apices facing inwardly toward one another.

Still another object of the invention resides in providing a device which is simple and durable in construction, inexpensive to manufacture and one which will be very efficient and useful in operation.

With these and other objects in view, our invention consists in the novel features of construction, combination and arrangement of parts as will be hereinafter referred to and more particularly pointed out in the specification and claims.

In the accompanying drawing forming a part of this application—

Figure 1 is an elevation of a grid plate constructed in accordance with our invention; and

Figure 2 is an enlarged fragmentary section therethrough as seen on the line 2—2 of Figure 1.

In describing the invention we shall refer to the drawing in which similar reference characters designate correspondings parts throughout the several views, and in which 1 designates the outer frame work of the grid plate which is preferably rectangular in design and may be of any desired thickness. Formed integral with the upper portion thereof adjacent one side edge is a projection 2 through the medium of which the plate may be secured to the cover of the battery.

Extending diagonally of the frame work 1 and having the outer faces thereof flush

with the opposite faces of the frame work are two main series of parallel ribs 3 and 4. The ribs 4 are arranged in staggered relation to the ribs 3. As stated above, these ribs extend diagonally of the frame work 1, being cast integral therewith and said ribs are connected together by diagonal ribs 5 which extend in a direction opposite to the direction of the ribs 3 and 4, as appears obvious from Figure 1 of the drawing, where it will be seen that the diagonal ribs 5 are composed of short triangular prisms joined together and turned in opposite directions to grip the alternate ribs of the two main series.

The ribs 3 and 4 are designed triangular in cross section and the apices thereof face inwardly toward one another so as to provide adhering or bearing faces on the ribs which also face inwardly. In this manner the material within the battery box may adhere to the faces of the ribs and be securely held to the grid plate. Considerable difficulty has been encountered heretofore in the use of grid plates, due to the fact that no provision has been made for the retention of the material to the ribs or other formations on the grid plate, but it will be seen that with a construction such as we have illustrated and described in the present application, this difficulty will be overcome and the maximum efficiency obtained from the use of such grid plate. The diagonal disposition of the ribs will greatly assist the particular construction of said ribs in the retention of the material thereto.

From the foregoing description it will be seen that we have provided a simple, inexpensive and efficient means for carrying out the objects of the invention.

While we have particularly described the elements best adapted to perform the functions set forth, it is obvious that various changes in form, proportion and in the minor details of construction may be resorted to without departing from the spirit or sacrificing any of the principles of the invention.

Having thus described our invention, what we claim is:

1. A grid plate comprising a frame, two main series of parallel ribs extending in like diagonal direction across said frame and arranged in staggered relation, and auxiliary ribs extending transversely to said first-

- named ribs, said auxiliary ribs being composed of joined members that are alternately united with the ribs of said first-named series. 40
5. 2. A grid plate comprising a frame, two main series of parallel ribs extending in like diagonal direction across said frame and arranged in staggered relation, said ribs being triangular in cross section with their 10 apices facing inwardly and with their bases flushed with the opposite surfaces of said frame, and auxiliary ribs extending transversely to said first-named ribs, said auxiliary ribs being composed of joined members 15 that are alternately united with the ribs of said first-named series. 45
3. A grid plate comprising a frame, two main series of parallel ribs extending in like diagonal direction across said frame and arranged in staggered relation, said ribs being triangular in cross section with their apices 20 facing inwardly and with their bases flushed with the opposite surfaces of said frame, and auxiliary ribs extending transversely to said 25 first-named ribs, said auxiliary ribs being composed of joined triangular prisms that are alternately united with the ribs of said first-named series. 50
4. A grid plate comprising a frame, two main series of parallel ribs extending continuously in one diagonal direction only across said frame and arranged, one series 30 with respect to the other, to provide uniform spacing of the ribs, and transverse members 35 alternately connecting with the ribs of the two main series of ribs. 55
5. A grid plate comprising a frame, two main series of parallel ribs extending continuously in one diagonal direction only across the plate, and arranged, one series 60 with respect to the other, to provide uniform spacing of the ribs, and transverse connecting members extending continuously across the plate and alternately connecting with the ribs of the two main series of ribs. 65
6. A grid plate comprising a frame, two main series of parallel ribs extending continuously in one diagonal direction only across said frame and arranged, one series 70 with respect to the other, to provide uniform spacing of the ribs, and serrated transverse connecting ribs for connecting the two series of main ribs, the serrations connecting the ribs of one series of main ribs, and the ribs of the other main series of ribs connecting between the serrations of the transverse rib, said serrated ribs being alternately arranged with the serrations standing in opposite directions. 75
7. A grid plate comprising a frame, two main series of parallel ribs extending continuously in one diagonal direction only across the plate, and arranged, one series 80 with respect to the other, to provide uniform spacing of the ribs, and transverse members comprising serrated ribs alternately connecting with the two main series of ribs, and alternately arranged, in which the serrations stand in opposite directions, said arrangement of main and transverse ribs forming the bounds of oblong open spaces in the face of said grid, said serrations forming end walls to said spaces. 85

In testimony whereof we affix our signatures.

GEORGE DAVIS.
LAURENCE M. SAMUEL.
